of Ridgewood, N. J.

Application December 29, 1947, Serial No. 794,255

53 Claims. (Cl. 164—114)

1

The present invention relates to a machine for reading in and punching jacquard cards, comprising a plurality of punches, the number of which is equal to that of holes comprised in a row of jacquard weaving cards, arranged in front of a holder adapted to receive a jacquard card to be punched.

This invention has for its object to provide a machine for simultaneously punching all of the jacquard cards corresponding to the same pick of the design of a twill effect, as well as the easy reading in of the design, or the sketch.

To this end, through the action of a suitable device, said punches are coupled one by one with a lever provided with a driving pin which is subjected to the action of a guide connected with a member rotating at a substantially constant speed, said guide being able, through the driving of the driving pin, to pivot said lever and thus to cause the coupled punch to be displaced, whilst the pivoting angle of the lever and consequently the length of the punch stroke can be limited by means provided therefor, said means acting in such a manner that, the lever being locked at a dead point of its stroke, the punch remains stationary, or, the locking of the lever taking place at an intermediate position, the punch returns to its starting point without punching said jacquard card, the last mentioned locking being brought about by the action on a locking device, of one of a plurality of fingers carried by one of a plurality of intermittently moving endless bands, each of which has a number of the above-mentioned fingers, arranged in transverse and longitudinal rows, at right angles to each other, each longitudinal finger row corresponding to a weft thread of one colour, and the number of fingers in said row being at least equal to the numbers of threads in one twill effect, whereas an endless band is provided for each twill effect of the pattern to be transferred to the fabrics.

In a preferred embodiment of the invention, said rotating member is a disc and the guide, formed as grooves in one face of said disc, comprises a circular groove, the centre of which is on the rotation axis of the disc, a groove of substantially oval shape, one portion of which merges in the first groove and the other portion reaches near to said centre, and at least one secondary groove connecting the substantially oval-shaped groove with the circular one.

At the end of the portion common to the circular and oval-shaped grooves, at their bifurcation, as well as the places of bifurcation of the oval-shaped groove and the secondary grooves

2

there is a member, for instance a plate spring which normally forces the above-mentioned driving pin to follow the oval-shaped groove and consequently to draw near to the aforesaid centre, but which moves aside and permits the driving pin to engage in other grooves when said driving pin exerts a sufficient pressure upon the aforesaid member, which takes place when the lever to which the driving pin is secured is prevented from moving.

The abovesaid device, coupling the punches with the lever is formed as a drum which, on each idle stroke of the aforesaid driving pin lever, turns through an angle equal to 360° divided by the number of punches and is provided with tappets or drivers, the number of which equals that of the punches, said tappets being evenly spaced apart on the surface of said drum along a helix, said helix extending to the length of a pitch, and, as each punch is in the plane of movement of one of said tappets, when a tappet engages a punch, the latter is pushed against a piece connected with aforesaid lever.

Said piece is a beam extending along the punch row and provided with a recess, for instance a groove, which is engaged by a catch or lug provided on each punch, when a punch is pushed against the beam.

The holder in which the jacquard card to be punched is fitted, moves intermittently in a direction substantially at right angles to the direction of the punch alinement, whilst pausing whenever a punch executes its active stroke.

The displacement of said holder is controlled by said driving pin lever and takes place on the idle stroke of the latter. The punches for the cutting of the needle holes are on a line slightly inclined to the direction of the forward movement of the jacquard card and in such a manner that, when the first punches in the row are opposite to a row of needle holes in the jacquard card, the last punches in the row are at a distance from this side of the next needle holes row equal to the distance between aforesaid two adjacent rows divided by the punch number. Owing to said arrangement the card holder may be given a uniform forward movement when passing from a thread to the following one, whether the consecutive holes may be on a same row or on a following one.

The fingers which act on the locking devices of the driving pin lever are removably attached to their respective endless band, the latter being formed or provided, at the places where fingers may possibly be arranged, with means, for in-

stance holes, permitting said fingers to be attached.

Each of said endless bands is carried on two pulleys, the distance between the axes of which is adjustable, so that said band may be stretched to the desired extent.

At least one of said two pulleys is carried by a shaft common to all bands, so that said bands are travelling simultaneously and at the same speed.

The movement of said shaft is controlled by the driving pin lever, which, being connected with said shaft through a ratchet wheel, imparts to it, when accomplishing an idle stroke, a rotation through an adequate angle.

The aforesaid device, locking the driving pin lever, is formed as a lever of the first order, the first arm of which is provided with a hook which, when a finger acts on its second arm, functioning as a feeler, may engage a catch integral with said lever, said feeler being able, through the action of a lever, to be displaced along its oscillation axis and to be brought outside the path of the fingers.

The lever of the first order locking the aforesaid driving pin lever comprises a number of feelers equal to that of the endless bands, each of said feelers, as they are carried on a single shaft, being in front of one of said bands.

The machine according to the invention, which permits the simultaneous punching of all jacquard cards corresponding to a pick of the design, consists of several machines of the above described type which are disposed side by side, each machine being adapted to punch a particular kind (size or quality) of weft threads, whilst the corresponding endless bands are arranged one behind another, so that the respective feelers are controlled by the same lever.

The machine is provided with a roller supporting the designs and rotating, after the reading in and punching of each pick of the design, so that the number of displacements necessary for passing the whole height of the pattern, is equal to the number of picks which the designing of said pattern would involve.

The reading in of the design takes place by means of a needle intermittently moving before a pick of the design, one step being made on each idle stroke of the aforesaid driving pin lever. Further details and features of the invention will appear from the description of a reading in and punching machine for jacquard cards, which is given hereinafter by way of non-restricting example with reference to the accompanying drawing.

Figure 1 is a front elevation of a machine according to the invention.

Figure 2 is a side elevation of the same.

Figure 3 is a front view on an enlarged scale of the holders carrying the card to be punched, and the driving devices for said holders.

Figure 4 shows the ratchet-wheel of the holder and the driving rod for said wheel.

Figure 5 is a plan view of the punches and the device for coupling said punches with the driving pin lever, and a portion of a jacquard card.

Fig. 6 is a further view on an enlarged scale of a guide integral with a rotating member according to the invention.

Fig. 7 shows a driving device of a roller supporting a design.

In the figures, same reference characters indicate like parts.

The jacquard card reading in and punching

machine shown in the aforesaid figures, comprises a plurality of punches 1, the number of which equals the possible number of holes in a row of a jacquard weaving card, arranged in front of a holder 2 adapted to accommodate a jacquard card 3 to be punched. Through the action of a device 4, the punches 1 are coupled one by one with a lever 5 provided with a driving pin or tappet 6. This driving pin 6 is controlled by a guide integral with a member 7 rotating at a substantially constant speed, which guide, through the movement of the driving pin, pivots the lever 5 and thus causes the coupled punch to be displaced. The pivoting angle of the lever 5 and, consequently, the length of the stroke of the coupled punch may be limited by means provided therefor which act in such a manner that, while the lever 5 is locked at a dead point of its stroke, the punch to be coupled remains stationary or, while the locking of the lever 5 takes place in an intermediate position, the coupled punch is restored to its starting point without having punched the card 3. The last-mentioned locking is effected by the action on a locking device of one of the fingers 8 carried by one of the endless bands 9 moved intermittently and carrying each a number of fingers 8, arranged in transverse and longitudinal rows at right angles to each other, each longitudinal row of fingers 8 corresponding to a weft thread of one colour, and the number of fingers 8 being equal to the number of threads in a twill effect. An endless band 9 is provided for each twill effect of the pattern to be transferred to the fabrics.

The turning member 7 is a disc and the guide is formed as a groove in one of the sides of said disc.

The guide comprises a circular groove 10, the centre of which registers with the axis of revolution 11 of the disc 7, a substantially oval groove 12, a portion of which merges into the first groove 10 and the other portion of which draws near to the centre 11, and secondary grooves 13, 14, 15 connecting the substantially oval-shaped groove 12 with the circular groove 10. At the end of the portion common to the circular groove 10 and the oval-shaped groove 12, at their bifurcation as well as at the bifurcation points of the oval-shaped groove 12 and the secondary grooves 13, 14, 15 there are members 16, 17, 18 and 19, for instance plate springs, which normally force the driving pin 6 to follow the groove 12 and consequently to draw near to the centre 11, but move aside and allow the driving pin 6 to enter other grooves when the driving pin 6 exerts on them a sufficiently strong pressure, which takes place when the movement of the lever 5 is prevented. When the lever 5 is locked at the upper dead point of its stroke, the driving pin 6 follows the circular grooves 10, and, while the lever 5 remains stationary, the machine turns idly.

The driving pin 6 enters the groove 13 when, in order to prevent the punching of the card, a block 50 of suitable thickness, which prevents the downward movement of the punch 1, is placed on said card.

The driving pin 6 enters the groove 14 when the coupled punch 1 is stopped by a jacquard card serving as a model in the card repeating process.

The driving pin 6 enters the groove 15 when the lever 5 is locked by the locking mechanism actuated by one of the fingers 8.

The driving pin 6 travelling through the oval-

shaped grooves 12 causes the lever 5 to be sufficiently lowered for one of the punches 1 coupled with the lever 5 to punch the virgin card 3 fitted in the holder 2.

The device 4, coupling the punches 1 with the lever 5, is formed as a drum 20 turning on each idle stroke of the lever 5 through an angle equal to 360° divided by the number of punches 1. This drum 20 is provided with tappets or driving pegs 21, the number of which is equal to that of the punches 1 and which are evenly spaced apart on the surface of the drum 20 along a helix.

As said helix extends to a pitch and each punch 1 is in the path of one of the tappets 21, when one of said tappets contacts with a punch, the latter is pushed against a piece 22 integral with the lever 5. The piece 22 is a beam or girder extending along a row of punches 1 and having a recess, for instance a groove 23, which is engaged by a catch or lug 24 on each punch. The lever 5 has two parallel arms, arranged side by side, to which the ends of the beam 22 are attached by uprights 25. The driving pin 6 is carried by one of the two arms of the lever 5. The holder 2, on which is placed the jacquard card to be punched, moves intermittently in a direction substantially at right angles to the alignment direction of the punches 1, while pausing whenever one of the punches effects the active stroke.

The movement of the holder 2 is controlled by the lever 5 and takes place on the idle stroke of the latter. The holder 2 is provided with a worm 26 extending in the direction of its displacement and carrying, threaded on it, a ratchet wheel 27 of spatially fixed position. On the wheel 27 acts a rod 28 reciprocated synchronously with the pivoting movement of the lever 5 and engaging through the agency of a hook 29 with one tooth of said wheel when lever 5 executes an idle stroke. In the specific embodiment shown, rod 28 is directly attached to lever 5. Rod 28 is acted upon by a spring 30, which presses it against wheel 27, or, when the rod has been sufficiently lowered, against a guide 31. Holder 2 is provided with punches 32 adapted to cut peg holes and lacing or twine holes, and serving as stops for holding back the jacquard card during the needle hole punching process. The punches 32 are controlled by a lever 33 attached to holder 2 and driven manually.

The punches 1 for the needle hole punching are arranged on a line slightly inclined to the advance direction of the jacquard card and in such a manner that when the first punch 1 of the row is opposite to a needle hole row of the jacquard card, the last punch 1 is on this side of the next row of needle holes at a distance equal to the interval between two adjacent row of needle holes divided by the number of punches.

The fingers 8 are removably attached to their respective endless bands 9. To this end, these bands have, at the places where fingers may possibly be arranged, means for instance holes enabling said fingers to be attached.

Each endless band 9 is carried on two pulleys 34 and 35, the distance between the axes of which is adjustable, so that said band may be stretched to the desired extent.

Pulleys 34 and 35 are carried by shafts common to all bands 9, so that said bands will travel simultaneously and at the same speed. The motion of the shaft 36 on which the pulley 34 is mounted is controlled by lever 5 which, as it is connected with said shaft through a device comprising a ratchet wheel 37, imparts to it, when

accomplishing an idle stroke, a rotation through an adequate angle. A shoe 38 bearing on the edges of endless band 9 presses it against pulley 34. The contact of a finger 8 with the locking device of lever 5 takes place when the finger 8 is in the proximity of shoe 38. The latter presses on endless band 9 through rollers, so that the friction is materially reduced. The locking device for lever 5 is formed as a lever of the first order, the first arm 39 of which is provided with a hook which, when a finger 8 acts on its second arm 40, which functions as a feeler, may engage a catch 41 rigidly connected with lever 5. Through the action of a lever 42, the feeler 40 may be displaced along its axis of oscillation and brought out of the path of the fingers 8. The locking lever 39 for lever 5 comprises as many feelers 40 as there are endless bands 9, all these feelers being carried by a single shaft 43 and arranged each in front of one of the bands 9.

The machine comprises as many control levers as it has feelers and consequently each lever 42 is situated in front of one of the bands 9.

The jacquard card reading in and punching machine shown in the accompanying drawings and enabling to punch simultaneously several cards, comprises a plurality of machines of the above-described type, arranged side by side, each machine punching jacquard cards for one particular kind (one size or one quality) of weft threads. The endless bands 9, corresponding to a given twill effect, are arranged one behind another, so that their respective feelers 40 are controlled by the same levers 42.

The machine is provided with a roller 44 supporting the design 45 and rotating, after the readings and the punchings of each pick of the design, in such a manner that the number of the displacements required for causing the whole height of the pattern to pass, is equal to the number of picks that the designing of this pattern would involve.

The rotation of the roller is controlled by means of a system comprising a ratchet wheel 51, a pawl 52 and a lever 53 connected for instance, to the lever 33.

The reading of the design takes place by means of a needle 46 intermittently moved in front of a pick of the design, in such a manner that said needle makes a step on each idle stroke of the lever 5.

It is to be understood that the invention is in no way restricted to the above-described embodiment and that numerous modifications may be made therein, among others with respect to the shape, constitution, number and arrangement of its elements without departing from the scope of the present invention.

I claim:

1. A jacquard card reading in and punching machine comprising a number of punches equal to the number of possible needle holes in a row of a jacquard card, a holder for accommodating a card to be punched, the punches being arranged opposite said holder, a lever for displacing said punches, a device for coupling said punches one by one to said lever, a roller adapted to support the design and means for rotating said roller after the reading in and the punching of each pick of the design, in such a manner that the number of the necessary movements to pass the whole of the height of the pattern is equal to the number of picks which the designing of said pattern would involve, a reading in needle and means for moving said needle intermittently opposite a

pick of the design, at the rate of one step on every idle stroke of said lever.

2. The combination of a plurality of machines according to claim 25, arranged side by side, each machine being adapted to punch jacquard cards for a particular kind (one size or quality) of weft threads, the intermittently moving means which correspond to a given twill effect being disposed one behind another, so that their respective feelers can be controlled by the same shifting means.

3. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

4. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, a driving pin on said lever, a guide for said driving pin, a rotatable member connected with said guide, means for rotating said member at a substantially constant speed, said guide being able, when driven by said rotatable member, to coact with said driving pin to pivot said lever and thus cause the coupled punch to be displaced, and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

5. A jacquard card reading in and punching machine comprising a number of punches equal

to the number of possible needle holes in a row of a jacquard card, a holder for accommodating a card to be punched, the punches being arranged opposite said holder, a lever for displacing said punches, means for coupling said punches one by one with said lever, a driving pin on said lever, a guide for said driving pin, a rotatable member connected with said guide, means for rotating said member at a substantially constant speed, said guide being able, when driven by said rotatable member, to coact with said driving pin to pivot said lever and thus cause the coupled punch to be displaced, means for limiting the pivoting angle and consequently the length of the coupled punch stroke, said limiting means including a device for intermittently locking said lever, means operable to actuate said device, a plurality of intermittently moving endless bands, each of which corresponds to one of the weave effects of the pattern to be transferred to the fabric, a plurality of fingers on each of said endless bands, said fingers being arranged in transverse and longitudinal rows at right angles to each other and each longitudinal finger row corresponding to one weft thread of the weave effect, and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card.

6. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one with said lever, a driving pin on said lever, a rotatable disc formed in one side with a circular groove the center of which is on the axis of rotation of said disc, a substantially oval-shaped groove, one portion of which merges in said circular groove and the other portion of which reaches near to said center and at least one secondary groove connecting said substantially oval-shaped groove with the circular one, all of said grooves being adapted to be engaged by said driving pin at predetermined times, yielding means situated at the end of the portion common to said circular groove and said oval-shaped groove at their bifurcation and at the bifurcation places of the oval-shaped groove and the secondary grooves, said means being adapted to normally force said driving pin to follow said oval-shaped groove and consequently to draw nearer to said center, but to be brought aside and to permit said driving pin to enter other grooves when it exerts a sufficient pressure, which takes place when the lever carrying said driving pin is limited in its normal pivotal movement, means for rotating said disc at a substantially constant speed, the rotation of said disc causing through the engagement of said driving pin in said grooves, the pivoting of said lever and consequently the displacement of the coupled punch

and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particularly weave effect and the number of fingers in said longitudinal row being at least equal to a predetermined integral factor of the number of points at which the warp threads will overlie such weft thread in such weave effect, said device for intermittently locking said lever being operated by the successive action of said fingers.

7. A jacquard card reading in and punching machine comprising a number of punches equal to the number of possible needle holes in a row of a jacquard card, a holder for accommodating a card to be punched, the punches being arranged adjacent to said holder, a lever for displacing said punches, a drum adapted to couple said punches with said lever for their displacement thereby, said drum carrying a number of tappets equal to that of said punches and evenly spaced apart on the surface of said drum along a helix, said helix extending along the length of a pitch, a piece engageable by said punches and connected to said lever, each of said tappets being adapted to push their respective punches one by one into engagement with said piece, means for actuating said lever, and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

8. A jacquard card reading in and punching machine comprising a number of punches equal to the number of possible needle holes in a row of a jacquard card, a holder for accommodating a card to be punched, the punches being arranged adjacent to said holder, a lever for displacing said punches, a drum adapted to couple said punches with said lever for their displacement thereby, said drum carrying a number of tappets equal to that of said punches and evenly spaced apart on the surface of said drum along a helix, said helix extending along the length of a pitch, a beam extending along the punch row, and formed with a groove engageable by lugs on said punches, said beam being connected with said lever, each of said tappets being adapted to push their respective punches one by one into engagement with said groove, means for actuating said lever, and means for limiting at predetermined

times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

20 9. A jacquard card reading in and punching machine comprising a number of punches equal to the number of possible needle holes in a row of a jacquard card, a holder for accommodating a card to be punched, the punches being arranged adjacent to said holder, a lever for displacing said punches, said lever comprising two parallel arms extending side by side, a drum adapted to couple said punches with said lever for their displacement thereby, said drum carrying a number of tappets equal to that of said punches and evenly spaced apart on the surface of said drum along a helix, said helix extending along the length of a pitch, a beam extending along the punch row and formed with a groove engageable by lugs on said punches, the ends of said beam being attached respectively to the said two parallel arms of said lever, each of said tappets being adapted to push their respective punches one by one into engagement with said groove, a driving pin on one arm of said lever, a guide for said driving pin, a rotatable member connected with said guide, means for rotating said member at a substantially constant speed, said guide being able, when driven by said rotatable member, to coast with said driving pin to pivot said lever and thus cause the coupled punch to be displaced, means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

10. A jacquard card reading in and punching machine comprising a number of punches equal to the number of possible needle holes in a row of a jacquard card, a holder adapted to receive the jacquard card to be punched, means for moving said holder intermittently in a direction at a slight angle to the direction of alignment of said punches, while stopping for a time every time one of said punches accomplishes its active stroke,

11

the punches being arranged opposite said holder, a lever for displacing said punches, means for coupling said punches one by one to said lever, means for actuating said lever, and means for limiting the pivoting angle and consequently the length of the coupled punch stroke, said limiting means including a device for intermittently locking said lever, means operable to actuate said device, a plurality of intermittently moving endless bands, each of which corresponds to one of the weave effects of the pattern to be transferred to the fabric, a plurality of fingers on each of said endless bands, said fingers being arranged in transverse and longitudinal rows at right angles to each other and each longitudinal finger row corresponding to one weft thread of a weave effect and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary and said fingers operate said device to lock said lever at an intermediate position of its movement to cause the coupled punch to return to its starting point without having punched the jacquard card.

11. A jacquard card reading in and punching machine comprising a number of punches equal to the number of possible needle holes in a row of a jacquard card, a holder adapted to receive the jacquard card to be punched, means for moving said holder intermittently in a direction at a slight angle to the direction of alignment of said punches, while stopping for a time every time one of said punches accomplishes its active stroke, the punches being arranged opposite said holder, a lever for displacing said punches, means for coupling said punches one by one to said lever, means for actuating said lever, and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers, and the intermittent displacement of said holder being controlled by said lever on the idle stroke of the latter.

12. A jacquard card reading in and punching machine comprising a number of punches equal to the number of possible needle holes in a row of a jacquard card, a holder opposite to said punches for accommodating a card to be punched, an oscillatable lever for displacing said punches, means for coupling said punches one by one to said lever, means for oscillating said lever, a worm arranged on said holder and extending in the

12

direction of movement of the latter, a ratchet wheel of fixed location threaded on said worm, a link reciprocated synchronously with the oscillation of said lever and having a hooked end which engages a tooth of said ratchet wheel on each idle stroke of said lever and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

13. A jacquard card reading in and punching machine comprising a number of punches equal to the number of possible needle holes in a row of a jacquard card, a holder opposite to such punches for accommodating a card to be punched, an oscillatable lever for displacing said punches, means for coupling said punches one by one to said lever, means for oscillating said lever, a worm arranged on said holder and extending in the direction of movement of the latter, a ratchet wheel of fixed location threaded on said worm, a link pivoted on said lever and having a hooked end which engages a tooth of said ratchet wheel on each idle stroke of said lever, and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

14. A jacquard card reading in and punching machine comprising a number of punches equal to the number of possible needle holes in a row of a jacquard card, a holder opposite said punches for accommodating a card to be punched, punching means adapted to punch the peg holes and lacing holes in the said jacquard card fitted in said holder, said punching means being adapted to function as holding stops for the jacquard card during the punching of needle holes therein by said punches, a lever for displacing said needle hole punches, means for coupling said needle hole punches one by one with said lever, means for actuating said lever, and means for limiting at predetermined times the movement of said lever

and consequently the displacement of the coupled needle hole punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

15. A jacquard card reading in and punching machine comprising a number of punches equal to the number of possible needle holes in a row of a jacquard card, a holder opposite said punches for accommodating a card to be punched, a pivotable lever punching means carried by said holder and adapted to punch the peg holes and lacing holes in the jacquard card fitted in said holder, said punching means being adapted to function as holding stops for the said jacquard card during the punching of needle holes therein by said punches, a lever for displacing said punches, means for coupling said punches one by one with said lever, means for actuating said lever, and means for limiting at predetermined times the movement of said lever and consequently the displacement of the coupled punch, said limiting means including a device for intermittently locking said lever, a plurality of intermittently moving means, the number of which corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

16. A jacquard card reading in and punching machine comprising a number of punches equal to the number of possible needle holes in a row of a jacquard card, a holder for accommodating a card to be punched, the punches being arranged opposite said holder on a straight line slightly inclined to the direction of the forward motion of the jacquard card in such a manner that when the first punch in the line thereof is opposite a needle hole row of the jacquard card, the last punch in the line thereof is in advance of such needle hole row at a distance therefrom equal to the distance between two successive rows of needle holes on such card, a lever for displacing said punches, means for coupling said punches one by one with said lever, means for actuating said lever, and means for limiting at predetermined times the movement of said lever and consequently the displacement of the coupled punch, said limiting means including a device for intermittently locking said lever, a plurality of intermittently moving means, the number of which

corresponds to the number of weave effects of the pattern to be transferred to the fabric, and a plurality of fingers on each of said intermittently moving means, said fingers being arranged in transverse and longitudinal rows at right angles to each other and each longitudinal finger row corresponding to one weft thread of a particular weave effect and the number of fingers in said longitudinal row being at least equal to a predetermined integral factor of the number of points at which the warp threads will overlie such weft thread in such weave effect, said device for intermittently locking said lever being operated by the successive action of said fingers.

17. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled punch at predetermined times, said limiting means including a device for intermittently locking said lever, means operable to actuate said device, a plurality of intermittently moving endless bands, each of which corresponds to one of the weave effects of the pattern to be transferred to the fabric, a plurality of fingers removably attached to each of said endless bands, said fingers being arranged in transverse and longitudinal rows at right angles to each other and each longitudinal finger row corresponding to one weft thread of a weave effect and the number of fingers in said row being

18. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled punch at predetermined times, said limiting means including a device for intermittently locking said lever, means operable to actuate said device, a plurality of intermittently moving endless bands, each of which corresponds to one of the weave effects of the pattern to be transferred to the fabric, a plurality of pairs of pulleys adapted to support each of said endless bands, a plurality of fingers attached to each of said endless bands, said fingers being arranged in transverse and longitudinal rows at right angles to each other and each longitudinal finger row corresponding to one weft thread of a weave effect and the number of fingers in said row being

at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card.

19. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled punch at predetermined times, said limiting means including a device for intermittently locking said lever, means operable to actuate said device, a plurality of intermittently moving endless bands, each of which corresponds to one of the weave effects of the pattern to be transferred to the fabric, a plurality of pairs of pulleys adapted to support each of said endless bands, a rotatable shaft adapted to carry at least one of said pulleys in all pairs in common, means for rotating said shaft, whereby all bands are moving simultaneously at the same speed, a plurality of fingers attached to each of said endless bands, said fingers being arranged in transverse and longitudinal rows at right angles to each other and each longitudinal finger row corresponding to one weft thread of a weave effect and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card.

20. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled punch at predetermined times, said limiting means including a device for intermittently locking said lever, means operable to actuate said device, a plurality of intermittently moving endless bands each of which corresponds to one of the weave effects of the pattern to be transferred to the fabric, a plurality of pairs of pulleys adapted to support each of said endless bands, a rotatable shaft adapted to carry at least one of

said pulleys in all pairs in common, a device comprising a ratchet wheel for the operative connection of said lever to said shaft, said ratchet wheel imparting to said shaft a rotation through a predetermined angle on each idle stroke of said lever, a plurality of fingers attached to each of said endless bands, said fingers being arranged in transverse and longitudinal rows at right angles to each other and each longitudinal finger row corresponding to one weft thread of a weave effect and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card.

21. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled punch at predetermined times, said limiting means including a device for intermittently locking said lever, means operable to actuate said device, a plurality of intermittently moving endless bands, each of which corresponds to one of the weave effects of the pattern to be transferred to the fabric, a plurality of pairs of pulleys adapted to support each of said endless bands, means for pressing the edges of said bands against one pulley in each pair, a plurality of fingers attached to each of said endless bands, said fingers being arranged in transverse and longitudinal rows at right angles to each other and each longitudinal finger row corresponding to one weft thread of a weave effect and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card.

22. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled

punch at predetermined times, said limiting means including a device for intermittently locking said lever, means operable to actuate said device, a plurality of intermittently moving endless bands, each of which corresponds to one of the weave effects of the pattern to be transferred to the fabric, a plurality of pairs of pulleys adapted to support each of said endless bands, means for pressing the edges of said bands against one pulley in each pair, a plurality of fingers attached to each of said endless bands, said fingers being arranged in transverse and longitudinal rows at right angles to each other and each longitudinal finger row corresponding to one weft thread of a weave effect and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card, said means for pressing the bands against their pulleys being disposed close to said locking device.

23. A jacquard card reading in and punching machine comprising a number of punches equal to the number of possible needle holes in a row of a jacquard card, a holder for accommodating a card to be punched, the punches being arranged opposite said holder, a lever for displacing said punches, means for coupling said punches one by one to said lever, means for actuating said lever, and means for limiting the movement of said lever and consequently the displacement of the coupled punch at predetermined times, said limiting means including a device for intermittently locking said lever, means operable to actuate said device, a plurality of intermittently moving endless bands, each of which corresponds to one of the weave effects of the pattern to be transferred to the fabric, a plurality of pairs of pulleys adapted to support each of said endless bands, means for pressing the edges of said bands against one pulley in each pair, rollers interposed between said pressing means and the bands, a plurality of fingers attached to each of said endless bands, said fingers being arranged in transverse and longitudinal rows at right angles to each other and each longitudinal finger row corresponding to one weft thread of a weave effect and the number of fingers in said row being at least equal to a predetermined integral factor of the number of points at which the warp threads will overlie such weft thread in such weave effect, said device for intermittently locking said lever being operated by the successive action of said fingers, said lever, device and operable means being so constructed and arranged that said operable means actuates said device to lock said lever at a dead point of its movement to maintain the coupled punch stationary, and said fingers operate said device to lock said lever at an intermediate position of its movement to cause the coupled punch to return to its starting point without having punched the jacquard card.

24. A jacquard card reading in and punching

machine comprising a number of punches equal to the number of possible needle holes in a row of a jacquard card, a holder for accommodating a card to be punched, the punches being arranged opposite said holder, a lever for displacing said punches, a lug on said lever, means for coupling said punches one by one to said lever, means for actuating said lever, means for limiting at predetermined times the movement of said lever and consequently the stroke of the coupled punch, said limiting means including a plurality of intermittently moving means, the number of which corresponds to the number of weave effects of the pattern to be transferred to the fabric, a plurality of fingers on each of said intermittently moving means, said fingers being arranged in transverse and longitudinal rows at right angles to each other and each longitudinal finger row corresponding to one weft thread of a particular weave effect, and the number of fingers in said longitudinal row being at least equal to a predetermined integral factor of the number of points at which the warp threads will overlie such weft thread in such weave effect, a lever of the first order, the first arm of which is hooked at its free end and the second arm of which is adapted to function as a feeler normally situated in the path of said fingers, whereby when one of said fingers comes into contact with said second arm, the hooked end of said first arm is caused to engage said lug on the punch controlling lever to lock the latter, said second arm being shiftable out of said path along its axis of oscillation.

25. 25. A jacquard card reading in and punching machine comprising a number of punches equal to the number of possible needle holes in a row of a jacquard card, a holder for accommodating a card to be punched, the punches being arranged opposite said holder, a lever for displacing said punches, a lug on said lever, means for coupling said punches one by one to said lever, means for actuating said lever, means for limiting at predetermined times the movement of said lever and consequently the stroke of the coupled punch, said limiting means including a plurality of intermittently moving means, the number of which corresponds to the number of weave effects of the pattern to be transferred to the fabric, a plurality of fingers on each of said intermittently moving means, said fingers being arranged in transverse and longitudinal rows at right angles to each other and each longitudinal finger row corresponding to one weft thread of a particular weave effect, and the number of fingers in said longitudinal row being at least equal to a predetermined integral factor of the number of points at which the warp threads will overlie such weft thread in such weave effect, lever means including a first arm, the free end of which is hooked, as many second arms as there are intermittently moving means, and a single oscillatable shaft carrying all said arms, said second arms which are adapted to function as feelers, being arranged in front of their respective intermittently moving means in the path of longitudinal rows of said fingers, whereby when one of said fingers comes into contact with one of said feelers the hooked end of said first arm is caused to engage said lug on the punch controlling lever, said fingers being shiftable out of the path of such row of fingers along the axis of said shaft, and a number of means equal to the number of said feelers for shifting said feelers.

26. A jacquard card reading in and punching machine comprising means for intermittently punching successive needle holes in jacquard cards, means for progressively setting up said punching means to punch successive such holes in successive rows in the cards, and means for selectively rendering said punching means inoperative to punch needle holes for which such means has been set up, said selective means including a plurality of intermittently moving selector units, the number of which corresponds to the number of the different kinds of weft threads to be utilized in a particular weave effect, each of said selector units having a plurality of elements predeterminedly arranged thereon in transverse and longitudinal rows at right angles to each other, each longitudinal element row in a selector unit corresponding to a weft thread of one kind in the weave effect and the number of elements in each of such longitudinal rows being at least equal to a predetermined integral factor of the number of points at which the warp threads will overlie the weft thread corresponding to such longitudinal row in such weave effect, and means selectively actuated by said elements at intermittent intervals to prevent said punching means punching the corresponding holes for which the latter has been set up.

27. A jacquard card reading in and punching machine comprising means for intermittently punching successive needle holes in jacquard cards, means for progressively setting up said punching means to punch successive such holes in successive rows in the cards, means for selectively rendering said punching means inoperative to punch needle holes for which such means has been set up, said selective means including a plurality of intermittently moving selector units, the number of which corresponds to the number of the different kinds of weft threads to be utilized in a particular weave effect, each of said selector units having a plurality of elements predeterminedly arranged thereon in transverse and longitudinal rows at right angles to each other, each longitudinal element row in a selector unit corresponding to a weft thread of one kind in the weave effect and the number of elements in each of such longitudinal rows being at least equal to a predetermined integral factor of the number of points at which the warp threads will overlie the weft thread corresponding to such longitudinal row in such weave effect, means selectively actuated by said elements at intermittent intervals to prevent said punching means punching the corresponding holes for which the latter has been set up, and means for selectively bringing a corresponding longitudinal row in each of said selector units into simultaneous operative relation with said selectively actuated means.

28. A jacquard card reading in and punching machine comprising means for intermittently punching successive needle holes in jacquard cards, means for progressively setting up said punching means to punch successive such holes in successive rows in the cards, and means for selectively rendering said punching means inoperative to punch needle holes for which such means has been set up, said selective means including a plurality of intermittently movable selector units, the number of which corresponds to the number of weave effects of the pattern to be transferred to the pattern plus the number of the different kinds of weft threads to be utilized in each of such weave effects, each of said selector units having a plurality of elements predeter-

minedly arranged into transverse and longitudinal rows at right angles to each other, each longitudinal element row in a selector unit corresponding to a weft thread of one kind in a particular weave effect and the number of elements in each of such longitudinal rows being at least equal to a predetermined integral factor of the number of points at which the warp threads will overlie the weft thread corresponding to such longitudinal row in such weave effect, means selectively actuated by said elements at intermittent intervals to prevent said punching means punching the corresponding holes for which the latter has been set up, and means operable to selectively bring corresponding longitudinal element rows of the selector units of each weave effect into simultaneous operative relation with said selectively actuated means.

29. A jacquard card reading in and punching machine comprising a plurality of intermittently moving selector units arranged in longitudinal and transverse rows on the machine, the number of selector units in each of said longitudinal rows corresponding to the number of weave effects of the pattern to be transferred to the fabric and the number of selector units in each of said transverse rows corresponding to the number of the different kinds of weft threads to be utilized in the particular weave effect for which such row was set up, each of said selector units having a plurality of elements predeterminedly arranged into transverse and longitudinal rows at right angles to each other, each longitudinal element row in a selector unit corresponding to a weft thread of one kind in a particular weave effect and the number of elements in each of such longitudinal element rows being at least equal to a predetermined integral factor of the number of points at which the warp threads will overlie the weft thread corresponding to such longitudinal element row in such weave effect, means for holding a jacquard card for each longitudinal row of selector units, means for intermittently punching successive needle holes in the jacquard cards supported by said holding means, means for progressively setting up said punching means to punch successive such holes in successive rows in such cards, and means selectively actuated by said elements at intermittent intervals to prevent said punching means punching the corresponding holes for which the latter has been set up.

30. A jacquard card reading in and punching machine comprising a plurality of intermittently moving selector units arranged in longitudinal and transverse rows on the machine, the number of selector units in each of said longitudinal rows corresponding to the number of weave effects of the pattern to be transferred to the fabric and the number of selector units in each of said transverse rows corresponding to the number of different kinds of weft threads to be utilized in the particular weave effect for which each such row was set up, each of said selector units having a plurality of elements predeterminedly arranged into transverse and longitudinal rows at right angles to each other, each longitudinal element row in a selector unit corresponding to a weft thread of one kind in a particular weave effect and the number of elements in each of such longitudinal element rows being at least equal to a predetermined integral factor of the number of points at which the warp threads will overlie the weft thread corresponding to such longitudinal element row in such weave effect, means for holding a jac-

guard card for each longitudinal row of selector units, means for intermittently punching successive needle holes in the jacquard cards supported by said holding means, means for progressively setting up said punching means to punch successive such holes in successive rows in such cards, means selectively actuated by said elements at intermittent intervals to prevent said punching means punching the corresponding holes for which the latter has been set up, means operable to selectively bring corresponding longitudinal element rows of the selector units in each transverse row of the latter into simultaneous operative relation with said selectively actuated means, and means operable to selectively bring each transverse row of said selector units into operative relation with said selectively actuated means.

31. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, and control means for rendering said punching means inoperative to punch needle holes for which it has been set up, said control means including a plurality of selector units corresponding in number to the number of weave effects to be included in the pattern to be woven, each of said selector units having a plurality of elements predeterminedly arranged in transverse and longitudinal rows at right angles to each other, each longitudinal row in a selector unit corresponding to one weft thread of a particular weave effect and the number of elements in said longitudinal row being at least equal to a predetermined integral factor of the number of points at which the warp threads will overlie such weft thread in such weave effect, and means selectively operated by said elements at intermittent intervals to prevent said punching means punching the corresponding holes for which it has been set up.

32. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, means for intermittently actuating said punching means to punch the needle holes for which it has been set up, and means for preventing said actuating means operating said punching means to punch a needle hole at predetermined times, said last mentioned means including a plurality of selector units corresponding in number to the number of weave effects to be included in the pattern to be woven, each of said selector units having a plurality of elements predeterminedly arranged in transverse and longitudinal rows at right angles to each other, each longitudinal row in a selector unit corresponding to one weft thread of a particular weave effect and the number of elements in said longitudinal row being at least equal to a predetermined integral factor of the number of points at which the warp threads will overlie such weft thread in such weave effect, and means selectively operated by said elements at intermittent intervals to control the operation of said actuating means.

33. A jacquard card reading in and punching

machine comprising a holder for a jacquard card to be punched, means for intermittently punching successive needle holes in the jacquard card supported by said holder, means for progressively setting up said punching means to punch successive such holes in successive rows in such card, and control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, and means selectively actuated by said control elements at intermittent intervals to prevent said punching means punching the corresponding holes for which the latter has been set up.

34. A jacquard card reading in and punching machine comprising a holder for a jacquard card to be punched, means for intermittently punching successive needle holes in the jacquard card supported by said holder, means for progressively setting up said punching means to punch successive such holes in successive rows on such card, means for intermittently actuating said punching means to punch the needle holes for which the latter has been set up, and means controlling the actuating operation of said actuating means at predetermined times, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, and means selectively actuated by said control elements at intermittent intervals to control the operation of said actuating means.

35. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, means actuated by said punching means for progressively advancing said holder relative to said punching means to enable the production of successive rows of holes in the card without interruption in the action of said setting up means, and control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of

points at which the warp threads will overlie such weft thread in such weave effect, and means selectively actuated by said control elements at intermittent intervals to prevent said punching means punching the corresponding holes for which the latter has been set up.

36. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, means for progressively advancing said holder relative to said punching means, the direction of advancement of said holder relative to the direction of alignment of a row of holes punched by said punching means being at such an angle that said punching means is enabled to progressively punch successive rows of holes in the card without interruption in the action of said setting up means, and control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, and means selectively actuated by said control elements at intermittent intervals to prevent said punching means punching the corresponding holes for which the latter has been set up.

37. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means for progressively advancing said holder relative to said punching means without interruption of such progressive feed to enable the production of successive rows of holes in the card without interruption in the action of said setting up means.

38. A jacquard card reading in and punching machine comprising a holder for a jacquard card to be punched, means for intermittently punching successive needle holes in the jacquard card supported by said holder, a second punching means for punching the peg and lacing holes in the

jacquard card supported by said holder, said second punching means being adapted to function as holding stops for the jacquard card during the punching of holes therein by said needle hole punching means, means for progressively setting up said needle hole punching means to punch successive such holes in successive rows in such card, and control means for rendering said needle hole punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, and means selectively actuated by said control elements at intermittent intervals to prevent said needle hole punching means punching the corresponding holes for which the latter has been set up.

39. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, means progressively advancing said selector units with an intermittent motion, and means progressively advancing said holder relative to said punching means without interruption of such progressive feed to enable the production of successive rows of holes in the card without interruption in the action of said setting up means.

40. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of ele-

ments in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means for progressively advancing said selector units and said holder, said last mentioned means being constructed and arranged to simultaneously advance said selector units and said holder one step for each setting up operation of said setting up means.

41. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means connected to said selector units and said holder and actuated by said punching means, said last mentioned means being constructed and arranged to advance said selector units and said holder one step for each setting up operation of said setting up means.

42. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of said elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means selectively operable to transfer said selectively actuated means from its operative relation with a selector unit of one particular weave effect into operative relation with a selector unit of another weave effect.

43. A jacquard card reading in and punching machine comprising a holder for a jacquard card

to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of said elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means selectively operable to transfer said selectively actuated means from its operative relation with one of the element sets of a selector unit of one particular weave effect into operative relation with another of the element sets of such selector unit.

44. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of said elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means selectively operable to transfer said selectively actuated means from its operative relation with one of the element sets of a selector unit of one particular weave effect into operative relation with another of the element sets of such selector unit at the end of a complete cycle of the latter, and means operable to selectively transfer during the reading in and punching of a pick of the design said selectively actuated means from its operative relation with a selector unit of one particular weave effect into operative relation with a selector unit of another weave effect.

45. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, control means for rendering said punching means inoperative to punch needle holes for which the latter has been set up, said control means including a plurality of selector units correspond-

ing in number of weave effects to be included in the pattern to be woven, each of said selector units having a plurality of sets of control elements, each set of said elements corresponding to one weft thread of a particular weave effect and the number of elements in each set being at least equal to a predetermined integral factor of the number of points at which the warp threads will overlie such weft thread in such weave effect, means selectively actuated by said control elements at intermittent intervals to prevent said punching means punching the corresponding holes for which the latter has been set up, and means selectively operable to transfer said selectively actuated means from its operative relation with one of said element sets into operative relation with any one of the other element sets.

46. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, and control means for rendering said punching means inoperative to punch needle holes for which the latter has been set up, said control means including a plurality of selector units corresponding in number to the number of weave effects to be included in the pattern to be woven, each of said selector units being composed of a plurality of sets of control elements, all of the element sets of each selector unit being mounted for cyclic movement about a common fixed axis, and each set of said elements corresponding to one weft thread of a particular weave effect, the number of elements in each set being at least equal to a predetermined integral factor of the number of points at which the warp threads will overlie such weft thread in such weave effect, means for intermittently moving said element sets about their cyclic paths, and means selectively actuated by said control elements at intermittent intervals to prevent said punching means punching the corresponding holes for which the latter has been set up.

47. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, and control means for rendering said punching means inoperative to punch needle holes for which the latter has been set up, said control means including a plurality of selector units corresponding in number to the number of weave effects to be included in the pattern to be woven, each of said selector units being composed of a carrier having provided thereon a plurality of sets of control elements arranged in predetermined manner in accordance with a particular weave effect, each set of said elements on each carrier corresponding to one weft thread of the weave effect and the number of elements in each set being at least equal to a predetermined integral factor of the number of points at which the warp threads will overlie such weft thread in such weave effect, all of said carriers being mounted for cyclic movement about a common fixed axis, means for intermittently moving said carriers about their cyclic paths, means selectively actuated by said control elements in one

of said sets at intermittent intervals to prevent such punching means punching the corresponding holes for which the latter has been set up, and means selectively operable to transfer said selectively actuated means from its operative relation with one of said element sets into operative relation with another of such element sets.

48. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, a movable device adapted to support the design to be transferred to the fabric, means for intermittently moving said device to feed the design past a reading in device, a reading in device, and means for intermittently moving said reading in device over said movable device in a direction transverse to the direction of feed of the design, said moving means being so constructed and arranged that the number of necessary movements of one of such means to cause the complete scanning of the design in one direction is equal to the number of ground picks which the weaving of the design would involve, and the movement of the other of such means is at the rate of one step for each setting up operation of said setting up means.

49. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, means for selectively controlling said punching means, a device for reading in a design to be transferred to the fabric, means for intermittently moving the design past such reading device, means for intermittently moving said reading in device over the design in a direction transverse to the direction of feed of the design, said moving means being so controlled and arranged that the number of necessary movements of one of such means to cause the complete scanning of the design in one direction is equal to the number of ground picks which the weaving of the design would involve and the movement of the other of such means is at the rate of one step for each setting up operation of said setting up means, and means selectively operable during the step by step scanning of the design to control said punch controlling means.

50. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, means for selectively controlling said punching means, means for intermittently moving said punch controlling means in a step by step fashion, a device for reading in a design to be transferred to the fabric, means for intermittently moving the design past such reading in device, means for intermittently moving said reading in device over the design in a direction transverse to the direction of feed of the design, said moving means being so constructed and arranged that the number of necessary movements of one of such means to cause the complete scanning of the design in one direction

is equal to the number of ground picks which the weaving of the design would involve and the movement of the other of such means is at the rate of one step for each setting up operation of said setting up means, said other moving means and said selective control means being actuated in synchronism with each other, and means selectively operable during the step by step scanning of the design to control said punch controlling means.

51. A jacquard card reading in and punching machine comprising a holder for a jacquard card to be punched, means for intermittently punching successive needle holes in the jacquard card supported by said holder, means for progressively setting up said punching means to punch successive such holes in successive rows in such card, means for actuating said punching means as it is set up, and means for rendering said punching means inoperative to punch needle holes for which the latter has been set up, said control means including a plurality of selector units corresponding in number to the number of weave effects to be included in the pattern to be woven, each of said selector units having a plurality of sets of control elements, each set of such elements corresponding to one weft thread of a particular weave effect and the number of elements in each set being at least equal to a predetermined integral factor of the number of points at which the warp threads will overlie such weft thread in such weave effect, and means selectively actuated by said control elements at intermittent intervals and operable to restrict the punching stroke of said punching means at such intervals, thereby preventing such punching means punching the corresponding holes for which the latter has been set up.

52. A jacquard card reading in and punching machine comprising a holder for a jacquard card

40

to be punched, means for intermittently punching individual, successive needle holes in the jacquard card supported by said holder, means for progressively and without interruption setting up 5 said punching means to punch without interruption in the intermittent action of said punching means, individual such holes successively in each row and in successive rows in such card, and control means for selectively preventing said punching means punching the corresponding holes for which the latter has been set up.

53. A jacquard card reading in and punching machine comprising a holder for a jacquard card to be punched, means for intermittently punching 15 successive needle holes in the jacquard card supported by said holder, means for progressively setting up said punching means without interruption to punch successive such holes in successive rows in such card, means for intermittently actuating said punching means to punch the needle holes for which it has been set up, and means for preventing said punching means punching needle holes for which it has been set up at predetermined times, said punching and 25 actuating means being so constructed and arranged that said punching means is returned by said actuating means at such predetermined times to its starting point without having punched the jacquard card.
